(57) **CLAIM**

The ornamental design for an attachable mirror for transport applications, as shown and described.

DESCRIPTION

FIG. 1 is a rear elevational view of an attachable mirror for transport applications showing my new design;

FIG. 2 is a front elevational view thereof;

FIG. 3 is a top plan view thereof;

FIG. 4 is a bottom plan view thereof;

FIG. 5 is a right elevational view thereof; and,

FIG. 6 is a left elevational view thereof.

The broken lines shown throughout the drawing are for illustrative purposes only and form no part of the claimed design.
